UNITED STATES PATENT OFFICE.

FRITZ S. ZAISSER, OF NEW YORK, N. Y.

WINDOW CLOSURE.

Application filed September 27, 1927. Serial No. 222,223.

This invention relates to pervious window closures more especially to the type known as ventilators and screens. It is well understood by most persons that windows opened for the admission of air must be provided with some sort of closure, pervious to air but impervious to insects, if comfort and health are to be preserved by those occupying the house in which the windows are placed.

It is also well understood by most persons that the ordinary and well known ventilators or screens commonly sold as an article of commerce have many and serious defects. They are not insect tight; they afford one or more large passageways about the edges for drafts; they are insecure to such an extent, that in gusty weather, especially, they rattle and bang to a most irritating extent; they are so placed in the window that a child may knock them out by a light blow; they are difficult if not impossible to retain substantially in place partly collapsed when one desires to put his head out of the window to observe something outside, or to hang something outside on a line or on the side of the building; and it is comparatively easy for an intended intruder to collapse the screen from the outside for the purpose of entering through the window.

A principal object of applicant's invention is to provide a window closure of the pervious type which will be insect tight, not only over its main surface but also about the edges where the window sash and window frame contact with the closure and at such points will also be dust and grit tight.

A further object of applicant's invention is to provide a closure of the type specified which will, when put in place, afford no opportunity for intense drafts about its edges.

A further object of applicant's invention is to provide a closure of the type specified which will, when in place, be so securely held that rattling and banging will not be possible as a result of wind or other vibrations; that a child can not knock it out of the window by such a force as a child would be likely to exert and would find it difficult to remove in any event; that same may be retained quite securely in place partially collapsed; and that same would offer even more difficulty to an intended intruder to remove from the outside of the window.

Other objects and advantages will appear

as the description of a particular physical embodiment, and modifications thereof, selected to illustrate the invention progresses and the novel features will be particularly pointed out in the appended claims.

In describing the particular physical embodiment and modifications thereof, selected to illustrate the invention, reference will be had to the accompanying drawings and the several views therein, in which similar characters of reference designate like parts throughout the several views and in which:

Figure 1 is a fragmentary elevational view of a window frame and sash, together with a closure embodying applicant's invention in place therein, viewed from the inside; Fig. 2, is a cross sectional view on the plane indicated by the line II—II of Fig. 1, viewed in the direction of the arrows at the ends of the line; Fig. 3 is a cross sectional view on the plane indicated by the line III—III of Fig. 1, viewed in the direction of the arrows at the ends of the line; Fig. 4, is a fragmentary perspective view, partly in section illustrating among other claims an improved fastening or connecting means provided by applicant; Fig. 5, is a detail fragmentary cross sectional plan view of a window frame or casing and applicant's closure illustrating a means provided by applicant for fastening or retaining the lower portion of the closure in place; Fig. 6, is a detail fragmentary cross sectional elevational view of a window frame or casing and applicant's closure, illustrating by another view the same fastening or retaining means as shown by Fig. 5; Fig. 7, is a fragmentary cross sectional view illustrating a modification of applicant's main fastening or connecting means. Fig. 8, illustrates in cross-sectional plan view the construction of the frame of applicant's closure. Fig. 9, is a fragmentary cross sectional view illustrating a modification of applicant's main fastening or connecting means.

In Figure 1, numeral 1 designates the lower rail of the window sash. 2 designates the inside finish of the window frame. 3 is moulding forming the inside stop for the window sash. 4, best shown in Fig. 2, designates the parting strip. 5 the window sash channel for the inside window sash. 6, best shown in Fig. 3, designates the window sill or surface against which the lower rail of the inner sash rests when closed. This sill slopes gently outward as shown in Fig. 3.

Applicant's closure for the space formed by the window sash, the bottom rail of which is designated 1, when raised is essentially a telescoping frame corresponding with the ordinary and well known telescoping frame now commonly sold as a window screen. Applicant's frame is so made however, for a reason to be later explained, so that each side thereof lies in a plane. This is best shown by Fig. 8. The vertical end posts 7 are each made the depth of one section or leaf of the frame, as the distance between the arrows 8, and also in addition the depth of the other leaf, that is, each end post is double the thickness of each top or bottom rail of each leaf or section. By such construction the surfaces 11 and 12 lie in one plane parallel to the median vertical plane of the frame and surfaces 9 and 10 likewise lie in one plane. The bottom and top rails are held together in the usual manner in sliding relation by having a dovetail groove formed in each in which the double dovetail spline 13, best shown in Fig. 3, is inserted. By so making the frame the necessity of twisting the frame out of alignment when placing it in a window is avoided.

By constructing the frame of applicant's closure in the manner described, the end posts, when the frame is inserted in a window, may be caused to rest tightly against the outside surface of the mouldings 3 as each end of the window and so perfectly close the same to the entrance of insects or strong and intense drafts.

The two rails at the bottom of applicant's frame are constructed with a somewhat sharp lower corner, as 14, best shown in Fig. 3. This sharp lower corner may extend the whole length of the rail or only a portion thereof. This somewhat sharp edge or protuberance serves to prevent the frame from sliding down the gentle slope of the window sill, and on account of friction being reduced to a minimum, this construction permits of easy telescoping of the sections when in place in a window.

Each of the top rails of the section has fitted thereto either integrally or as a separate piece the shoulder or partial arcuate members, as 15 and 16. These members are formed as shown in Figs. 3 and 4 to interfit and slide with the sections one on or within the other. The arcuate or shoulder of the sliding member 15 is attached to one section as viewed in Fig. 1, and the shoulder member 16 is attached or made integral with the other section. Both members terminate at the top surfaces 17 and 18 substantially parallel with the adjacent side of the window sash rail 1, Fig. 1, and the surfaces are substantially in the plane of the surfaces 9 and 10 Fig. 8 of the frame, being eased off slightly or just sufficient to prevent damage thereto by a forcible closing of the window sash against

their top surfaces. By means of the shoulder members 15 and 16 the only remaining space between the window sash or window frame and applicant's frame is closed so that insects and drafts are avoided.

The shoulder members 15 and 16 also afford a ready means for determining whether the screen is in correct position in the window, because in the dark one may readily move a hand over the lower rail of the sash toward the frame. If the shoulder is present all along the lower edge of the sash the frame is properly in place.

In order to more securely hold the frame in place a series of one or more holes 19, are formed in the shoulder member 15 and a hole or cavity 20 in the window sash and a headed pin 21 is provided, which is placed in one of the holes 19 most closely adjacent the end of shoulder member 16 and which is also in line with the hole or cavity in the window sash. By this means the telescoping of the frame is substantially prevented by anyone except a person on the inside of the window and even then unless the pin 21 is first withdrawn, so that a small child could not in general reach the pin 21 and so could not collapse the frame with a purpose of climbing out of the window and pin penetrating window sash prevents child from raising window and climbing over screens.

By providing the shoulder members 15 and 16, each extending the full length of the section to which attached except for a short distance at the ends as shown in Fig. 1, at 22 and 23 the space normally open is closed but also in addition the frame is securely fastened in place so that it cannot sway and rattle and bang. It is held from inward movement by the contact between surfaces 9 and 10 and the mouldings 3 and from outward movement by shoulders 15 and 16 bearing against rail 1. The cut away portions 22 and 23 are just sufficient so that the end of shoulder 15 bears against the side of moulding 3 on one side of the window as viewed in Figs. 1 and 2, and the end of shoulder 16 bears against moulding 3 on the opposite side. By this means a slight crevice which would otherwise occur at 22 and 23 is prevented, and the frame may be properly inserted in any window no matter how tight the contact between the window sash and the mouldings 3. The lower edge of the bottom rail bears tightly against the sill 6 and is prevented from sliding out by the sharp corner or protuberances 14.

An additional construction to prevent the lower portion of the frame from moving outwardly is provided by placing small dowel pin in one or both sections. This is shown in Figs. 5 and 6 in which the dowel pin in the left hand section is shown and designated 24, placed to enter a cavity 25 formed in the window frame. These dowel pins may be

used with or in addition to or as an alternative for the sharp corner or protuberance 14.

As the opposite top section of the sliding frame members has contact with the window rail at three points, due to the arcuate construction of the shoulder there is a minimum resistance to the movement of the sliding members so that it may be easily collapsed or telescoped while the frame is in place for the purpose of getting at the outside.

Members 15 and 16 as shown in Fig. 3, may be constructed in many ways, two alternate types of which are illustrated and shown in Figs. 7 or 9.

The purpose of any of the various forms of construction of this frame or device is for suitable adaption of a material 25 Fig. 4, which may be of any suitable material, which can be used as a ventilator or screening.

The construction of this frame permits the adoption of material to be used with applicant's invention for any desired protection such as insects, drafts, or any other elements 25 not wanted. Its principal object is the security against rattling or banging and the possible onslaught of small children, cats, dogs, etc., and the fact that applicant's device is easy to put in or take out or partially collapse while in place to give access to the outside and is a more definite security against the attempts of intruders than the materials now used for screening or ventilating.

The frame described may be constructed of 35 various materials, wood or metal being preferred.

Although applicant has illustrated and described a particular physical embodiment of his invention and some modifications thereof 40 and explained the principle, construction and modification of operation thereof, nevertheless, the forms illustrated and described are merely illustrative and do not exhaust the possible physical embodiment of means 45 underlying the invention.

What is claimed as new and desired to be secured by Letters Patent of the United States, is:

1. In a window closure, of the general type 50 having two substantially rectangular frames supporting a pervious material and positioned parallel and adjacent with means attaching them together and causing them to be 55 slideable one on the other for increasing and reducing the combined length, in combination: end posts, one for each frame; top rails, 60 one for each frame; bottom rails, one for each frame, the faces of each end post on one side of the closure lying in a plane parallel to the medium longitudinal plane of the closure, and the faces of the bottom rails lying both in the 65 same plane that of the bottom faces of the end posts; top rails one for each frame; shoulder members, one for each frame, each shoulder member attached to the top rail of its frame and each formed to slide substantially 70 in contact with the other, both shoulder members terminating in a surface lying substantially in the plane of the faces of the end posts, and each shoulder member terminating at the end thereof adjacent an end 75

top rail of its frame and each formed to slide substantially in contact with the other, both shoulder members terminating in a surface lying substantially in the plane of the faces of the end posts, and each shoulder member terminating at the end thereof adjacent an end post short of the outside face of the adjacent end post and one of the shoulder members provided with a plurality of orifices whereby a pin like member may be passed therethrough and into an adjacent window sash rail.

2. In a window closure, of the general type having two substantially rectangular frames supporting a pervious material and positioned parallel and adjacent with means attaching them together and causing them to be slideable one on the other for increasing and reducing the combined length, in combination: end posts, one for each frame; top rails, one for each frame; bottom rails, one for each frame, the faces of each end post on one side of the closure lying in a plane parallel to the median longitudinal plane of the closure, and the faces of the bottom rails lying both in the same plane, that of the bottom faces of the end posts, said bottom rails being formed with a sharp edge for a portion of its length; top rails, one for each frame; a shoulder member, one for each frame, each shoulder member attached to the top rail of its frame and each formed to slide substantially in contact with the other, both shoulder members terminating in a surface lying substantially in the plane of the faces of the end posts, and each shoulder member terminating at the end thereof adjacent an end post short of the outside face of the adjacent end post and one of the shoulder members provided with a plurality of orifices whereby a pin like member may be passed therethrough and into an adjacent window sash rail.

3. In a window closure, of the general type having two substantially rectangular frames supporting a pervious material and positioned parallel and adjacent with means attaching them together and causing them to be slideable one on the other for increasing and reducing the combined length, in combination: end posts, one for each frame; top rails, 110 one for each frame; bottom rails, one for each frame, the faces of each end post on one side of the closure lying in a plane parallel to the median longitudinal plane of the closure, and the faces of the bottom rails lying both in the same plane that of the bottom faces of the end posts; top rails, one for each frame; shoulder members, one for each frame, each shoulder member attached to the top rail of its frame and each formed to slide substantially in contact with the other, both shoulder members terminating in a surface lying substantially in the plane of the faces of the end posts, and each shoulder member terminating at the end thereof adjacent an end 115

post short of the outside face of the adjacent end post and one of the shoulder members provided with a plurality of orifices whereby a pin like member may be passed there-
5 through and into an adjacent window sash rail, and a dowel pin extending outwardly from an end post adjacent the bottom for in-
sertion in an orifice of a window casing.

4. In a window closure, in combination: an
10 extensible frame carrying a pervious material and formed for making tight contact at the bottom and two sides and having means at the top for making tight contact with the face of a window sash rail, said means formed
15 with cut away portions to avoid the front stops of a window frame.

5. In a window closure, in combination: an extensible frame carrying a pervious material and formed for making tight contact at the

bottom and two sides and having means at the top making tight contact with the face of a window sash rail, said means formed with cut away portions to avoid the front stops of a window frame, and provided with means for attachment to a window sash rail for hold-
20 ing the frame in place and preventing col-
lapsing from the outside.

6. In a window closure, in combination; a pervious sheet; a second pervious sheet; means including interfitting and telescopic 30 sections each supporting a pervious sheet and each provided with a top rail of means attached to each section and terminating in surfaces in the same plane one with the other for bearing upon the face of a window sash rail.

FRITZ S. ZAISSER.
